UNITED STATES PATENT OFFICE

109,153

DESIGN FOR A COMBINED RADIO AND PHONOGRAPH CABINET

Henry T. Roberts, Chicago, Ill., assignor to See-burg Radio Corporation, Chicago, Ill., a corporation of Illinois

Application January 17, 1938, Serial No. 74,361

Term of patent 7 years

To all whom it may concern:

Be it known that I, Henry T. Roberts, a citizen of the United States and a resident of Chicago, in the county of Cook and State of Illinois, have invented a new, original, and ornamental Design for a Combined Radio and Phonograph Cabinet, of which the following is a specification, reference being had to the accompanying drawings, forming part thereof.

Figure 1 is a perspective view of a combined radio and phonograph cabinet showing my new design.

Figure 2 is a top plan view thereof on an enlarged scale.

Figure 3 is a sectional view on the line 3—3 of Figure 1.

Figure 4 is a front elevational view thereof partly broken away for convenience of illustration; and

Figure 5 is an end elevational view partly in section on the line 5—5 of Figure 4.

I claim:

The ornamental design for a combined radio and phonograph cabinet, substantially as shown and described.

HENRY T. ROBERTS.
